MICHAEL J. MAGUTEH, OF CARLSTADT, NEW JERSEY.

FEEDING MECHANISM.

Application filed July 23, 1925, Serial No. 45,485, and in Great Britain March 23, 1925.

- The present invention relates generally to improvements in feeding mechanisms and is more especially directed to mechanisms for feeding articles, such as hooks and eyes, to be fastened on tape or other flexible strip material, although my invention is not limited to operation in conjunction with the articles named, its uses being varied as will be apparent from the following specification.
- 10 For the purpose of affording a clear understanding of the invention, I shall describe a certain embodiment thereof, which is designed for feeding garment hooks formed from wire or stamped from sheet metal, into 15 position to be affixed, by eyelets or other devices, to a tape or strip of woven material or the like.
- In the accompanying drawings in which the aforesaid embodiment is illustrated,
- 20 Figure 1 is a front elevation of the hopper and cooperating elements of my improved feeding mechanism.
- Figure 2 is a rear elevation of the structure shown in Figure 1.
- 25 Figure 3 is a side elevation of the mechanism shown in Figures 1 and 2.
- Figure 4 is a sectional view on the line 4—4 of Figure 1.
- Figure 5 is an enlarged sectional detail, 30 taken on the line 5—5 of Figure 1, to show the hook ejecting means.
- Figure 6 is a bottom plan view of a segment of the hopper, showing the article guideways.
- 35 Figure 7 is an elevation, partly in section, on the line 7—7 of Figure 6.
- Figure 8 is a section on the line 8—8 of Figure 6.
- Figure 9 is a plan view of one of the yield- 40 able article engaging elements of the hopper.
- Figure 10 is an enlarged detail of the agitator actuating levers, and
- Figure 11 is a transverse section on the line 11—11 of Figure 3.
- 45 Referring now to the drawings in detail, in which like characters of reference are employed to designate like parts, in the several views, 12 indicates the wall of the hopper which is annular in shape, and 13 the base 50 to which the wall is fixed by means of the screws 14. Centrally located on the rear face of the base 13 is a protuberance or boss 15 which is bored as clearly shown in Figure 4 to form a bearing for the shaft 16, the said 55 protuberance or boss 15 functioning as a stub
- shaft or hub for the hopper. This shaft or hub 15 is revoluble within the bearing 17 formed integral with or rigidly fixed to the arms 18, 19 and 20 of the bed-plate 21, which is suitably supported from the standards 22 and 23, as by the cross-member 24 and the brackets 25 and 26 carried thereon. The brackets 25 and 26 are adapted to be bolted to the extensions 21^a and 21^b of the bed-plate as shown at 27, relative adjustment being 60 permitted by the provision of the slots 25^a and 26^a in said brackets.
- Journalized in the bearings 28 and 29 is a shaft 30, adapted to be driven through the medium of the belt 31 traveling on the pulley 32, when the clutch members 33 and 34 are engaged by the actuation of the lever 35. Any suitable clutch mechanism may be used, that in the present showing embodying a grooved collar 36 slidable longitudinally of 70 the shaft, within which the upper end 35^b of the lever 35 rides. As the lever is rocked in one direction on its pivot 35^a, the clutch members 33 and 34 are yieldingly engaged by the action of the spring 37, the movement of 75 the lever 35 in the reverse direction obviously effecting the disengagement of said members. A stop 38, fixed to the end of the shaft 30 limits outward movement of the collar 36. A bevel gear 39 is keyed to the other end of 80 the shaft 30 in mesh with a bevel gear 40 fixed to the vertically disposed shaft 41, journaled in the bearings 42 and 43, the latter bearing being integral with the arm 20.
- Keyed to the shaft 41, intermediate of its 85 ends, is a driving cam 44 of the so-called screw type, having active and inactive surfaces, the former of which are laid out to at all times engage two of the projecting pins or studs 45 fixed to the ring 46, which is fastened to the base 13 of the hopper so as to rotate said hopper with an intermittent or step-by-step movement, when the aforesaid clutch members 33 and 34 are in engagement. The said ring 46 is preferably fastened to the base 90 13 by screws 47 in engagement with the dependent flange 13^a thereof which surrounds the extruded portion formed by the provision of the depression 13^b in the center of the inner face of the base.
- Abutting upon the face of the aforesaid depression 13^b, is a hub 48 pinned, or keyed, to the shaft 16, which supports a segmental member 49, preferably of the configuration shown, carrying a plurality of flexible fingers 100
- 105 110

50, the said member being oscillated or rocked within the hopper as the latter rotates, for the purposes hereinafter described. This rocking movement of the member 49, which 5 may be termed an agitator, is obtained through the medium of the levers 51 and 52 and the link 53, the lever 51 being pinned to the shaft 16 while the lever 52, which is mounted to rotate with the shaft 41, is connected to the offset end 51^a of the lever 51 by the link 53. From this arrangement, it will be seen that as the short lever 52 revolves with the shaft 41, the link 53 will be reciprocated to rock the lever 51 and with it the shaft 10 16 (see Figure 10).

The wall 12 of the hopper, which may be formed of any suitable material, preferably brass, is provided with equi-distantly spaced bores or openings, as indicated at 54. As 20 these bores which are provided throughout the circumferential area of the wall, are identical in plan and function, but one of them, as shown in Figure 8, will be described. The bore, which is cylindrical, extends from the 25 top of the wall of the hopper to a point adjacent the lower edge thereof, where the diameter is reduced as at 55 by the formation of a shoulder 56. Positioned in the bore is a tubular member 57 having a base 57^a provided with a central orifice 57^b to form a bearing for the pin 58, the head of which normally abuts upon said base 57^a under the influence of the spring 59 which is confined within said tubular member, between the 30 head of said pin and the shoulder 60^a of the plug 60 which is frictionally retained within the slotted end of the tubular member, as shown in Figure 9. The tubular member 57 is fitted within the bore 54 for reciprocable 35 movement as the spring 61, which is held between the base 57^a thereof and the base of the bore, is compressed and expands, as herein-after described, a ring 62^a perforated to register with and pass over the protruding plugs 40 60 so as to engage the upper ends of the respective tubular members 57 serving to retain them in functioning relation.

As will be seen from Figure 6, the bottom 50 of the hopper wall is provided with a plurality of angularly disposed equidistantly spaced shoulders 62, each of these shoulders having an abutment 64 spaced inwardly of its respective edges, the inner ends of these abutments being rounded or curved as shown. 55 The base 13 is adapted to lie in close contact with the abutments 64 when in position as heretofore described and is fastened to certain of them by the screws 14 threaded into the openings 14^a.

60 It will be noted that the laterally spaced shoulders 62 and the abutments 64 thereon, provide a series of angularly disposed guideways having two levels, the intermediate portion, lying between the parallel edges of 65 the shoulders 62 being of greater depth than

the portions on either side thereof formed by the abutments 64 and the top faces of the shoulders 62. The relative depths of the aforesaid stepped portions of the guideways are determined by the sizes of the work which is to be passed therethrough. For instance, in operating with garment hooks, as shown, the intermediate channel 63 is of a depth slightly greater than the thickness of the body 70 of the hook and its overlying nib, while the depth of the shallow part of the guideway, between the abutments 64 and the edges of the shoulders 62 which define the channel 63, is just sufficient to permit the relatively flat 75 head or eye-forming portion of the hook to pass between the base 13 and the opposed spaced faces of the shoulders 62.

Fixed to the bed-plate 21, by means of screws or the like 68 is an arcuate member, or retainer, 66 which is recessed throughout 80 its length, the inner edge thereof projecting within the undercut 65 of the lower peripheral edge of the hopper wall 12. This recess, indicated at 67, is of the same depth as the shallow or head-receiving portions of the 85 hopper guideways. As the hopper revolves, as heretofore described, a plurality of the hopper guideways are in moving registration with the aforesaid recess, which, in effect, constitutes a continuation of the shallow part 90 of each thereof, for the purposes which will become apparent.

Supported from the bed-plate 21 by the brackets 69 and in superposed relation to the 100 hopper ring 62, is a segmental member 70, the under surface at each end thereof being bevelled or chamfered as indicated at 71 so that as the hopper rotates upon its axis, the ends of the plugs 60 will ride thereunder to effect the depression of the tubular members 105 57 against the tension of their springs 61 and simultaneously project the ends of the pins 58 through their respective bores 55 into the passage 63.

110 Mounted on the bed-plate 21 and fastened thereto as by screws 72 is a chute 73, having a centrally disposed groove or guideway of two depths, as shown at 74 in Figure 11, the upper end of said guideway being open as at 75 for observation purposes. In order that the hooks may be delivered to the tape or other flexible medium in proper position to be fastened thereto, they must be fed to the chute 74 in a predetermined position, that is, head foremost, with the nib of the shank 115 uppermost, the hooks traversing said chute one behind the other as shown in Figure 3.

Now, assuming that a quantity of hooks is supplied to the hopper through the mouth 120 76 of the cover 77 which is provided with windows 78 of transparent material, as mica, it is evident that they will fall by gravity to the lowermost portion of the rotating hopper, that within the zone of the retaining member 66 where they will accumulate in a 125

relatively deep pile in various positions, which pile is continuously agitated by the fingers 50 of the segmental member 49.

Since, as explained, the channel 63 of the 5 hopper guideway is of a depth to receive the body and superposed nib of the hook, while the shallow lower level of said guideway on either side of the channel 63 can only accommodate the relatively flat lateral eye-forming extensions of the head of the hook, it will be obvious that a hook may enter a hopper guideway only when the surface of its nib is next to the inner face of the top of the channel 63. As the hopper rotates, the agitation 10 of the pile will effect the separation of individual hooks therefrom, those in proximity to the inner ends of the hopper guideways which are in position to enter the same dropping thereinto by gravity or under the influence of the flexible fingers 50 of the 15 agitator which have a wiping contact with the wall of the hopper, it being evident that some hooks will enter the guideways head first, while others will be received in the 20 reverse position.

The movement of the hooks which enter the hopper guideways head first (the correct position to admit them to the chute 73) will be arrested with their heads partly within 25 the shallow portions of the guideways and partly within the registering recess 67 of the member 66, the distance between the bore 55 and the wall of the recess 67 being slightly greater than the overall length of the hook 30 (see Figure 6). The continued rotation of the hopper will bring the hopper guideways into sequential registration with the mouth of the chute 73, formed by the members 73^a and 73^b, as they pass beyond the end of the 35 retaining member 66, thus permitting the hooks to gravitate into the chute head foremost.

Where a hook has entered the hopper guideway in the other of the two positions 40 in which it may be received, that is, nib first, it cannot clear the bore 55 because of the obstruction offered by the shallow recess 67 of the member 66, which the relatively thick nib portion of the hook cannot enter, but 45 means must be provided to prevent it entering the mouth of the chute 73 as the guideways pass beyond the end of said member. To accomplish this, the lower end of the aforesaid segmental member 70 is disposed in 50 a position slightly in advance of the terminus of the retaining member 66 (see Figure 1) to engage the plug 60 of the tubular member 57 associated with that guideway which is just clearing the end of said retaining member, and depress the same against the tension 55 of the spring 61. The end of the pin 58 is thereby projected through the bore 55 and, due to the spring 59, yieldingly engages the shank of the hook and holds it within the 60 guideway until the spring 61 returns to its

normal position as the plug 60 completes its transit of the segmental member 70 and is released, when the hook drops back into the hopper. As will be seen from Figure 6 of the drawings, with the head of a hook in the 65 correct position to be deposited in the chute 73, the projection of the pin 58 through its opening 55 will not interfere with the ejection of the hook from the guideway at the proper time, as its shank will lie beyond the 70 bore 55 owing to the head of the hook being disposed within the shallow recess 67 of the retaining member, as before stated.

Should an improperly located hook remain 75 in a guideway after it has been released by the pin 58, I have provided an ejecting mechanism having a finger 79 which is adapted to enter the respective hopper guideways as they come into alignment therewith. This finger 79 having an attaching end 79^a is secured to the block 80 which is reciprocable within the guide 81 on the bed-plate 21, the said block having an arm or extension 82 protruding through a slot 83 in said bed-plate. Mounted on the shaft 30 is a step 85 cam 84, the active surface of which is adapted to engage the cam follower or pin 85 carried by the lever 86. This lever is slotted as 90 at 87 to reciprocate upon the shaft 30, between the hub of said cam and the collar 88 and is 95 pivotally connected to said arm or extension 82 at 89, a tension spring 90 being connected to the projecting pin 91 on said arm or extension and to a stud 92 on the bed-plate 21.

From this arrangement of the ejector 100 mechanism, it will be evident that as the cam 84 traverses the pin 85, the block 80 will be moved upwardly in its bearing to the position shown in Figure 5, this being accomplished in synchronism with the rotative 105 movement of the hopper. As the hopper becomes stationary in its step-by-step movement, the block 80 moves downwardly under the influence of the spring 90 which functions as the cam follower leaves the peak of said 110 cam 84. In this manner, each guideway, as it comes into alignment with the finger 79 is penetrated and cleared.

In the event of a slowing up or stoppage 115 in the delivery of the hooks from the outlet of the chute 73 which would result in an overflow as the hopper continues to rotate and feed, I provide a plate of the configuration shown at 93 in Figure 1 which is pivoted to the bed-plate 21 at 94, a spring 95 mounted 120 on the stud 96 and in engagement with the pin 97, bearing against the arm 98 of said plate to hold the nose 99 thereof in a position relative to the discharging guideway whereby the flange 100 will serve to direct the overflow of hooks to the receptacle 101 suitably supported from the bed-plate or the standard 23.

What is claimed is:

1. A feeding mechanism embodying a hop-

130

per provided with spaced peripheral outlets for the articles contained therein, a chute cooperatively associated with said hopper, means for intermittently rotating said hopper to sequentially bring said outlets to delivery position with relation to said chute whereby articles disposed in a predetermined position within said outlets will enter said chute, means actuatable for releasably retaining within said outlets those articles which are not in such predetermined delivery position, and mechanically actuated means timed to enter each of said outlets when said hopper is at rest to clear the same of obstructions.

15 2. A mechanism for feeding garment hooks to a machine for fastening the same on tape or the like, comprising a hopper having circumferentially spaced outlets, each outlet being formed to receive a hook in either of two predetermined positions, means for intermittently rotating said hopper to sequentially bring said outlets to discharging position, means cooperatively associated with said outlets and actuatable to releasably retain therein those hooks which are in one of said two predetermined positions, and means cooperating with said outlets to permit of the discharge therefrom of those hooks which are in the other of said two predetermined positions.

30 3. A mechanism for feeding garment hooks to a machine for fastening the same on tape, comprising a hopper having spaced peripheral outlets formed to receive said hooks in either of two predetermined positions, a chute associated therewith, means for agitating the hooks in said hopper whereby they will enter said outlets by gravity, means cooperatively associated with said hopper outlets to retain therein the hooks which are in one of said predetermined positions and to permit their discharge into said chute, and means actuatable for releasably retaining within said outlets those hooks which are not in correct position for discharge therefrom.

45 4. A mechanism for feeding garment fastening devices to a machine for securing the same to a fabric, comprising a hopper provided with circumferentially equidistantly spaced outlets for the fastening devices contained therein, a chute cooperatively associated with said hopper and adapted to transport the devices only in a predetermined position, means embodied within said outlets for permitting the fastening devices contained within said hopper to enter the same by gravity in either of two predetermined positions, means for intermittently rotating said hopper, means for permitting the discharge from said outlets into said chute of those fastening devices contained therein in one of said predetermined positions, means actuatable for releasably retaining within said outlets the fastening devices disposed therein in the other of said predetermined po-

sitions, and means functioning in synchronism with the driving means of said hopper to enter said outlets and eject therefrom any fastening devices which may remain therein following their release by said retaining means.

5. A mechanism for feeding garment hooks to a machine for fastening the same on fabrics, comprising a hopper, means for intermittently rotating said hopper, circumferentially disposed outlets at the base of the wall of said hopper for the hooks contained therein, each of said outlets being shaped to receive a hook only when its nib is in the uppermost position, means for agitating the hooks within said hopper to permit the same to enter said outlets, a chute, means associated with said hopper and said chute to permit the hooks disposed within said outlets in one of two predetermined positions to enter said chute, means for retaining within said outlets those hooks which are in the other of said predetermined positions during the movement of said outlets past the discharging position, means for rendering said retaining means ineffective at a predetermined point in the rotative movement of said hopper to permit the hooks held in the outlets thereby to return to the hopper, and means functioning in synchronism with the hopper driving means to enter said outlets in sequence to clear the same of obstructions.

6. A mechanism for feeding garment hooks, of an elongated shape having a flat shank embodying a head portion wider than the shank, and a nib overlying and spaced from said shank, for fastening the same on a support, including a hopper provided with peripheral outlets formed to permit the passage of a hook therethrough with its nib in the uppermost position, means for intermittently rotating said hopper, means for releasably retaining within said outlets those hooks whose head portions are inwardly disposed and means effective when the hopper is at rest to clear the outlets of obstructions.

7. A mechanism for feeding garment hooks having a shank and an overlying nib portion, for fastening the same to a support, embodying a hopper having peripheral openings formed to permit of the passage of hooks therethrough when the nibs thereof are upwardly disposed, means effective for retaining within said openings those hooks which are not in a predetermined position for ejection from said openings, a chute and means cooperating with said chute and said hopper to permit the hooks freely supported within said openings to pass to said chute.

8. A mechanism for feeding irregularly formed articles, embodying a hopper having peripheral outlets formed to receive such articles in two predetermined positions, means for intermittently rotating said hopper, a chute adapted to receive the articles from the

hopper when in a predetermined position, and spring actuated means associated with said hopper for releasably retaining within said outlets those articles which are disposed 5 therein in one of said two predetermined positions.

9. A mechanism for feeding articles of irregular formation to a receiving medium, including a hopper having peripheral outlets 10 conformed to receive such articles in a predetermined position, means for intermittently rotating said hopper, a chute adapted to receive articles from said hopper when such articles are disposed in the aforesaid 15 predetermined position, spring supported means carried by said hopper and adapted to engage articles within said outlets, when such articles are disposed in positions other than their predetermined position, means for 20 rendering said spring supported means effective as article retainers during a part of the rotative movement of said hopper and means functioning in synchronism with said hopper driving means adapted to enter said outlets, 25 when the hopper is at rest, to clear the same of obstructions.

10. A hopper for a feeding mechanism for delivering garment hooks to a mechanism for fastening the same upon fabric, provided 30 with equi-distantly spaced peripheral outlets for the hooks contained therein, each of said outlets having spaced surfaces co-operating to form a guideway having a major and a minor transverse dimension, said guideway 35 being adapted to receive a hook only when its nib portion is locatable within the minor dimension thereof, means cooperatively associated with said hopper for permitting the egress from said outlets of those hooks which 40 have entered the guideway's head foremost and means functioning to retain within said outlets the hooks disposed therein in the reverse position.

11. A mechanism for feeding garment 45 hooks to a machine for fastening the same on fabric, comprising an annular hopper, means for intermittently rotating said hopper, means for delivering hooks to said hopper, equi-distantly spaced peripheral outlets for 50 the hooks contained within said hopper, each

of said outlets having spaced surfaces cooperating to form a guideway having a major and a minor transverse dimension, adapted to receive a hook only when its nib portion is locatable within the minor dimension thereof, oscillating means having yieldable elements for agitating the hooks within said hopper towards said outlets, a chute for delivering the hooks to their supporting fabric, 55 fixed means cooperating with said hopper and said chute for permitting of the egress from said outlets of those hooks which have entered the guideway's head foremost, spring supported plungers located in the wall of said hopper, hook engaging elements yieldably connected to said plungers, said elements being adapted to enter said outlets, fixed means formed to engage said plungers during the rotative movement of said hopper to depress the same in opposition to their springs, whereby said elements will be pressed into yielding engagement with the hooks in said outlets which have entered the guideway's shank foremost, means for effecting the release of the plunger-element retained hooks at a predetermined point in the 70 rotative movement of said hopper and a reciprocable member functioning in synchronism with the hopper driving means adapted to enter said outlets in sequence to clear the 75 same of obstructions.

12. A mechanism for feeding garment hooks to a machine for fastening the same on a flexible support, comprising a hook receiving and carrying device provided with spaced 80 peripheral outlets formed to receive hooks in either of two predetermined positions, a delivery device associated with said hook receiving and carrying device, means cooperating with said hopper for retaining within said outlets hooks in one of said two predetermined positions, means for permitting the hooks in the other of said two predetermined positions to enter said delivery device from 85 said outlets and means for moving said hook receiving and carrying device to sequentially bring the peripheral outlets thereof into hook-discharging association with said delivery device.

MICHAEL J. MAGUTH.
